UNITED STATES PATENT OFFICE

KOSTANTZ KLEPADLO AND ALEXANDER GRATKOWSKI, OF SCRANTON, PENNSYLVANIA

BEAM-HANDLING APPARATUS FOR COAL-MINING AND OTHER OPERATIONS

Application filed September 10, 1929. Serial No. 391,556.

This invention relates to certain new and useful improvements in beam or log handling apparatus for coal mining and other operations.

5 The primary object of the invention is to provide an apparatus for the positioning of roof beams or timbers and side posts in the room or passage of a coal mine, it having heretofore been customary to employ manual labor at the risk of life and limb in the positioning of these beams and timbers, the apparatus disclosed in this application efficiently handling the beams and timbers and setting them into correct positions in a minimum 15 of time and at a great saving of labor.

With the above and other objects in view that will become apparent as the nature of the invention is better understood, the same 20 consists in the novel form, combination and arrangement of parts hereinafter more fully described, shown in the accompanying drawings and claimed.

In the drawings:—

Figure 1 is a side elevational view of a 25 beam handling apparatus constructed in accordance with the present invention and illustrating by dotted lines the beam handling or crane arms of the apparatus in their lowered positions to be engaged with a beam, and 30 further illustrated by dotted lines in their raised and elevated positions, for the placing of a head or roof beam in a mine room or the like;

Figure 2 is a fragmentary front elevation 35 view, showing the beam engaging rod supporting a ceiling or roof beam that has been placed in engagement at its ends with upright columns or posts;

Figure 3 is a fragmentary front elevational 40 view;

Figure 4 is a vertical cross-sectional view taken on line 4—4 of Figure 1, showing the turn table mechanism of the apparatus and the operating means therefor;

45 Figure 5 is a vertical cross-sectional view taken on line 5—5 of Figure 1;

Figure 6 is a detail sectional view taken on line 6—6 of Figure 5;

50 Figure 7 is a detail sectional view taken on line 7—7 of Figure 5;

Figure 8 is a fragmentary side elevational view, partly in section showing the detail construction of one of the beam handling arms and clamping jaw carried thereby; and

55 Figure 9 is a fragmentary side elevational view of one of the beam handling arms showing the clamping jaw in its opened position.

In mining operations, it is required that the roofs or ceilings of rooms and certain 60 passages or tunnels through the mines be supported or braced to prevent collapse of the roofs or ceilings and it has heretofore been customary to employ manual labor in hoisting the ceiling or roof beams into position and in many instances, serious injury has

65 resulted to men engaged in this work. The primary object of this invention is to provide portable apparatus movable over mine tracks and manually operated for the handling and

70 positioning of beams in the rooms, tunnels or passages of mines in placing the beams in vertical positions as side supports and in also disposing them adjacent the ceiling or roof.

75 In the accompanying drawings, as illustrated in Figure 1, the beam handling apparatus

comprises a truck or platform 1 mounted upon track wheels 2 that ride upon the mine track 3 and when the apparatus is rigidly set for a beam handling operation, chock blocks 4 are associated with the wheels and tracks, 80 while anchor chains 5 pass around the track rails and through openings provided in the track wheels.

85 A turn table construction is mounted upon the truck or platform 1 and includes a circular bearing plate 6 anchored to the platform by the tie bolts 7, shown in Figures 4 and 5 and upon which plate a turn table 8 carrying the beam handling mechanism is rotatably mounted by the center bearing 9,

90 opposed circular grooves in the faces of the disk plate 6 and turn table 8 having ball-bearing races 10 for the reduction of friction. The devices for effecting rotation of the turn

95 table 8 include a circular series of gear teeth 11 on the underside of the peripheral edge of the turn table that is engaged by the gear wheel 12 having a bearing 13 on one side edge of the platform 1, the shaft 14 to which the gear wheel 12 is fixed extending beyond the

75

85

90

95

100

bearing 13 as shown in Figure 5 to receive an operating crank handle 15. The turn table 8 is held in rotatably adjustable position by the two dogs 16 pivotally mounted upon the platform 1 and movable into engagement with the gear wheel 12.

The beam handling arms are of identical construction and the elements associated with each beam handling arm comprise a pair of guide bars 17 extending upwardly from the turn table 8 at a slight inclination as shown in Figure 9 with a cross-brace 18 extending between the rear edges of the guide bars as shown in Figures 4 and 8. A beam handling arm 19 is pivotally supported at its lower end as at 20 between the guide bars 17, while a cross brace 21 as shown in Fig. 3 connects the arms 19 adjacent their upper ends. The beam handling arm 19 is longitudinally socketed as at 22, the socket extending from the outer end to a point adjacent the pivot mounting 20 for the reception of the extension arm 23, the outer end 24 of the beam handling extension arm 23 being shouldered as at 25 for engagement with the outer end of the arm 19 for limiting inward movement of the extension arm into the socket 22 as shown in Figure 8. A beam gripping clamp or jaw is carried by the outer end 24 on the extension arm 23, the curved jaw 26 being formed integral with the arm end 24 while the cooperating gripping jaw 27 is pivotally mounted as at 28 upon the end 24 of the extension arm. The two extension arms 23 are independently operable so that one arm may be advanced or extended a greater distance than the other arm when it is desired to place ceiling or roof beams at an angle and this operating mechanism includes the provision of rack teeth 29 upon one side edge of the extension arm 23 to be engaged by the pinion 30 fixed to the shaft 31 journaled in the guide bars 17 with a crank handle 32 fixed to the projecting end of each shaft 31. Upon rotation of the shaft 31, the pinion 30 operates the extension arm 23 for moving the same into and out of the socketed beam handling arm 19. The beam handling arms 19 being pivotally mounted as at 20 between the lower ends of the guide bars 17, it is intended that the arms be retained against pivotal movement during the operation of shifting the extension arms 23, the forward edges of the side bars 17 and the upper forward side of the socketed beam handling arm 19 being provided with openings 33 that are adapted to register when the arm is moved between the guide bars for the reception of a locking pin head 36 carried by a chain 37 attached to the upper ends of a side bar of each pair. The extension arms 23 are independently adjustable so that one may be extended a greater distance than the other to position ceiling or roof beams at an inclination when required. Means is provided for holding the extension arms 23 in shifted po-

sitions and includes a dog 33 pivoted on a cross piece 34 between adjacent guide bars 17 that is movable into engagement with the pinion 30 to hold the same against movement.

When the pins 36 are removed from the registering openings 33 in the beam handling arms 19 and guide bars 17, the arms 19 lower by their own weight upon their pivotal mounting 20 to the dotted line position shown in Figure 1 and the mechanism for regulating the pivotal or lowering movement of the beam handling arms and also for raising them with a beam positioned in the clamping jaws 26 and 27 is carried by the turn table 8 and includes a pair of standards 38 supported at their lower ends on the turn table and placed by angle bracket plates 39 as shown in Figures 1 and 8 bolted thereto and to the turn table, and also the outer guide bar 17 of each pair. Brace bars 40 extend between the upper ends of the standards 38 and guide bars 17 for the rigid support of these elements as shown in Figure 8. As shown in Figures 1 to 5, a shaft 41 is journaled in the upper ends of the standards 38 with a crank handle 42 detachably mounted upon each end thereof, the shaft 41 carrying a pair of spaced grooved cable guide blocks 43, one adjacent each end thereof between the standards 38 and a pair of centrally positioned gear wheels 44. A second shaft 45 is journaled in the upper ends of the standards 38 rearwardly of the shaft 41 and at its outer end is provided with a ratchet wheel 46 engaged by the pivoted dog 47 upon the upper end of the standard 38, the central portion of the shaft 45 carries a pair of gear wheels 48 meshing with the gear wheels 44 upon the shaft 41. The shaft 45 outwardly of the gears 48 and inwardly of the standards 38 have cables 49 wound thereon as at 49a with the end of the cable secured to the shaft, the cables passing over the guide blocks 43 with the other ends thereof, each associated with a clamping jaw 110 at the outer end of the beam handling extension arm 23.

Each cable 49 is associated with a grooved guide block 50 journaled between the rear upper end of the adjacent guide bars 17 with the terminal end thereof associated with a pair of clamping jaws 26 and 27. As shown more clearly in Figs. 4, 8 and 9, the cable 49 passes through an opening 51 in the clamping jaw 27 and over a grooved guide block 52 journaled in the opening 51 and around a grooved guide block 53 journaled in the opening 54 in the fixed clamping jaw 26, the terminal end of the cable 49 returning to the movable clamping jaw 27 and anchored thereto as at 55. The outer face of the movable clamping jaw 27 is provided with a series of ratchet teeth 56 to be engaged by one end of a pawl 57 that is pivotally mounted as at 58 upon the outer end 24 of the extension arm 130

23 with the other end of the pawl 57 spring pressed as at 59 for normally holding the pawl in engagement with the ratchet teeth on the pivoted clamping jaw 27.

5 With the truck or platform 1 anchored to the track 3 as shown in Fig. 1, the apparatus is ready for use. The pins 36 are then removed from the openings 35 and the dogs 47 disengaged from the ratchet wheels 46, the beam handling arms 19 and extensions 23 carried thereby then moving by their own weight on their pivotal mountings 20, the speed of descent being controlled by the cables 49 wound upon the shaft ends 45 which may be unwound therefrom by the crank handles 42. When the arms are lowered, the cables 49 move into engagement with the guide blocks 50 upon the upper ends of the guide bars 17 as shown in Figure 1. The beam 20 A to be positioned adjacent the ceiling or roof of a mine room, tunnel or passage is positioned across the track 3 upon supporting blocks B. The pawls 57 are then released from the clamping jaw sections 27 to permit them to move upon their pivotal mounting 28 shown in Figure 9 so that the pointed ends of the clamping jaws 26 and 27 may be engaged with the beam A as shown in Figure 1. The shaft 41 is then rotated by the crank 30 handle 42 for rotating the shaft 45 to wind the cables 49 thereon, initial movements of the cables 49 by their particular association with the clamping jaws 26 and 27 causing the latter to bite into the beam A for the positive engagement therewith. Continued rotation of the shaft 45 winding the cables 49 thereon elevates the beam arms 19 upon their pivotal 35 mountings 20, raising the beam A to the position shown in Figure 2, and at which time the beam handling arms 19 are positioned between the guide bars 17 with the openings 35 therein in registration. The pins 36 are then inserted in the openings to lock the arms 19 to the guide bars 17. The dogs 47 are then 40 disengaged from the ratchet wheel 46 to permit free rotation of the shaft 45 and the shafts 32 are then operated by the crank handles 32 to rotate the pinions 31 for elevating the extension arms 33 out of the socketed beam handling arms 19 for elevating the beam A to a point adjacent the ceiling or roof of the mine room or the like. As shown in Figure 2, vertical beam C more previously positioned and the beam A is then lowered into 45 engagement with the upper ends of the beam C, the ends of the beam A being mitered as illustrated, while the usual wedge pieces are inserted between the beam A and the ceiling or roof of the mine room. The pawls 57 are then 50 disengaged from the clamping jaw member 27 to permit disengagement of the clamping jaws from the beam A and the extension arms 23 are then lowered into the sockets 22 of the arms 19. The apparatus is also employed for mounting the vertical beams C

in position, and while the beam A is illustrated as being positioned transversely of the track 3, it is to be understood that in the turn table mounting 8, the apparatus may be employed for the handling of beams and other mine equipment positioned at either side of the track 3, and also on the track at either side of the truck 1.

70 From the above detailed description of the invention, it is believed that the construction and operation thereof will at once be apparent, and while there is herein shown and described the preferred embodiment of the invention, it is nevertheless to be understood that minor changes may be made there- 75 in without departing from the spirit and scope of the invention as claimed.

We claim:—

1. Apparatus of the character described comprising a truck, a turn table thereon, 80 beam handling mechanism on the turn table, including pairs of guide bars, a beam handling arm pivoted between each pair of guide bars, means for locking the arms to the guide bars, an extension on each arm 85 having gripping jaws at its outer end, and operating means for the extension.

2. Apparatus of the character described comprising a truck, a turn table thereon, beam handling mechanism on the turn table, 90 including pairs of guide bars, a beam handling arm pivoted between each pair of guide bars, and provided with an elongated end opening socket, an extension arm therein 95 having rack teeth on one side, a manually rotatable pinion engaged with the rack teeth for projecting and retracting the extension arm, and means for locking the arms to the 100 guide bars.

3. Apparatus of the character described comprising a truck, a turn table thereon, beam handling mechanism on the turn table, 105 including pairs of guide bars, a beam handling arm pivoted between each pair of guide bars, and provided with an elongated end opening socket, an extension arm therein having rack teeth on one side, a manually rotatable pinion engaged with the rack teeth for projecting and retracting the extension arm, 110 means for locking the arms to the guide bars, standards on the turn table, a manually rotatable shaft on the standards, and cables wound on the shaft, each connected to an arm extension for raising the extensions.

4. Apparatus of the character described comprising a truck, a turn table thereon, beam handling mechanism on the turn table, including pairs of guide bars, a beam handling arm pivoted between each pair of guide bars, and provided with an elongated end 120 opening socket, an extension arm therein having rack teeth on one side, a manually rotatable pinion engaged with the rack teeth for projecting and retracting the extension arm, 125 standards on the turn table, a manually rotat-

able shaft on the standards, cables wound on the shaft, each connected to an arm extension for raising the extensions, the gripping jaws comprising a fixed jaw and pivoted jaw, and ratchet mechanism associated with the pivoted jaw for holding the same in closed position, the connection between the cables and arm extensions consisting of anchoring the cable to the pivoted jaw and looping the same through the fixed jaw whereby the pivoted jaw is moved toward the fixed jaw when the cable is operated to raise the arms.

5. Apparatus of the character described comprising a truck, a turn table thereon, beam handling mechanism on the turn table, including pairs of guide bars, a beam handling arm pivoted between each pair of guide bars, and provided with an elongated end opening socket, an extension arm therein having rack teeth on one side, a manually rotatable pinion engaged with the rack teeth for projecting and retracting the extension arm, means for locking the arms to the guide bars, standards on the turn table, a manually rotatable shaft on the standards, cables wound on the shaft, each connected to an arm extension for raising the extensions, the gripping jaws comprising a fixed jaw and a pivoted jaw, and ratchet mechanism associated with the pivoted jaw for holding the same in closed position, the connection between the cables and arm extensions consisting of anchoring the cable to the pivoted jaw and looping the same through the fixed jaw whereby the pivoted jaw is moved toward the fixed jaw when the cable is operated to raise the arms.

In testimony whereof we affix our signatures.

KOSTANTZ KLEPADLO.
ALEXANDER GRATKOWSKI.
